UNITED STATES PATENT OFFICE

HARRY HERTZBERG, OF BROOKLYN, NEW YORK, ASSIGNOR, BY MESNE ASSIGNMENTS, TO THE M. PROPP CO. INC., OF NEW YORK, N. Y., A CORPORATION OF NEW YORK

ELECTRIC ATTACHMENT PLUG AND FITTING

Application filed June 23, 1926. Serial No. 117,899.

This invention relates to electrical fittings and deals more specifically with attachment plugs and current taps.

An object of this invention is to provide a plug or current tap of improved construction which will enable a plurality of branch circuits to be detachably joined thereto and fed simultaneously from a single power source.

10 Another object of this invention is to provide an improved attachment plug or current tap comprising few and simple parts, which is cheap to construct and which is practical and efficient in operation to a high degree.

15 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a perspective view of an attachment plug embodying my invention.

Fig. 2 is a front elevational view of the improved plug with one of the base sections removed to expose the interior construction.

Fig. 3 is a front elevational interior view of the other base section.

Fig. 4 is a cross-sectional view taken on line 4-4 in Fig. 1.

Fig. 5 is a front elevational plan view of a current tap fitting embodying the invention showing a portion broken away to expose the interior.

40 Fig. 6 is a plan view of a blank from which the current carrying member is formed.

Figs. 7 and 8 are perspective views showing other modified forms of the invention.

45 Referring in detail to the drawings, 10 denotes an improved attachment plug embodying the invention which is formed with the base sections 11 molded of any suitable insulating material well known in this art. The sections 11 are all made in the same form of mold and any two may be placed in face to

face relation to form a casing for the electrical connections. The bolts 26 hold the sections together. Each molded section 11 is provided with the cavities 12 and connecting grooves 13 which are formed to fit current carrying members 18 which lie therein, end passages 14 being provided for contact blades 25 which are joined to the current carrying members 18. The outer portions of the sections 11 which contain the cavities 12 may be formed with flat outer faces and rounded ends. These portions contain sockets 22 for receiving the blades of other plug caps C as shown in Fig. 4. The portions over the end passage 14 may be of reduced thickness and suitably formed to complete the top of the plug which carries the connecting blades.

The current carrying members 18 which extend into the sockets 22 are preferably formed from a single blank of suitable springy conducting sheet material. (See Fig. 6). Said blank having extensions 19 and 20 which are bent on opposite sides and folded with respect to the body 18a of the blank to provide spring contacts for the blades of plug caps C which may be inserted in the slots 22. Nipples or protuberances 21 may be stamped on the extensions 19 and 20 to cooperate with corresponding holes which may be formed on the blades of the plug caps in the well understood manner. The over-folded portions 23 of members 18 which are formed by the extensions 19 and 20 and the body 18a of the blank are bent so that they lie in planes at right angles to each other and are connected at 24 with the blades 25. It should be noted here that when one of the members 18 is placed on edge in its slots 12 and groove 13, one of the extension (say 19) is folded upwardly, while the other (20) is folded downwardly. Another blank is similarly bent and placed in the other slots 12 and groove 13. The pairs of overfolded portions 23 which are diametrically opposite each other are parallel and also have their extensions 19 or 20 bent in the same direction, that is either upwardly or downwardly.

45 Blades 25 are joined to the conductors 18 in any suitable manner, as by riveting, these blades being of the usual plug cap type and 100

being adapted to detachably connect with a suitable current tap in the well understood manner.

Thus, four separate plug caps C may be inserted in the slots 22 and make contact with both current carrying members 18 by means of its folded extensions 19 or 20. This permits of four separate circuits being connected in parallel across the terminals 25. It is apparent that the attachment plug 10 may be constructed to accommodate any desired number of plug cap C by simply elongating the section and providing the required slots and adding to the current carrying members.

In the fitting 110 shown in Fig. 5, I substitute the cord 30 for the terminal blades 25. This fitting is similar in construction to the plug 10 shown in Fig. 1 in all other details and is adapted for the special purpose of being permanently connected to a portable cord and functioning as a terminal current tapping plug, to which other circuits may be joined as explained above.

Figs. 7 and 8 each, indicate a plug 210 and fitting 310 similar to that shown in Figs. 1 and 6, respectively, except that they are adapted to receive but two connecting plug caps instead of four. The conductors and slots in these modifications are formed in a manner similar to that described above except that the current carrying members thereof form a single pair of sockets on each side of the plug or fitting instead of a double socket.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:—

1. An attachment plug comprising a base, a pair of conductors carried thereby, means formed to extend from opposite edges of one of said conductors each adapted to form one terminal respectively of separate contact pairs, means similarly formed on the other of said conductors each adapted to form the other terminal respectively of said separate contact pairs, said pairs being positioned in crossed relation and adapted to connect with terminal blades inserted from opposite sides of the bases and means to connect said conductors to a source of electricity.

2. An attachment fitting comprising a base, a pair of conductors carried thereby, pairs of oppositely extending portions on one of

said conductors, each portion adapted to form one terminal respectively, of separate contact members, similar portions formed on the other of said conductors, each adapted to form the other terminal respectively of separate contact members, said members forming pairs positioned in crossed relation adapted to connect with terminal blades inserted from the opposite sides of the base.

3. An attachment fitting, a conductor therefor comprising an elongated strip, pairs of portions extending from opposite edges of said strip, each pair of oppositely extending portions forming spring contacts disposed at right angles to each other adapted to receive terminal blades of a plurality of plug caps inserted from each of the opposite sides of the attachment fitting.

In testimony whereof I affix my signature.

HARRY HERTZBERG.
